PENCIL SHARPENER

Johannes Ficker and Emil Eckert,
Munich, Germany

Application May 13, 1935, Serial No. 21,247

8 Claims. (Cl. 120—93)

This invention relates to a lead pencil sharpener and particularly to a pencil sharpener in which safety razor blades may be utilized as the cutting instrumentality effective to shave the wood and cut the graphite core.

It is an object of this invention to produce a knife holder and to provide a guide for the pencil in order that the pencil may be brought into such relation to the blade that when the pencil 5 is turned in the guide in engagement with the blade, a tapered point will result by a device that has a pleasing appearance and is without external projecting parts that might cause injury or damage to furniture or to the highly finished 10 objects or clothing with which it might come in contact.

It is a further object of this invention to provide a body having novel means for holding a blade in operative relation to the guide in which 15 the lead pencil is presented to the blade, the said means for holding the blade being yieldable in order that it may operate in conjunction with blades of different sizes, within predetermined bounds, and to provide means for collecting the 20 lead that is displaced during the sharpening operation.

It is furthermore an object of this invention to provide means for allowing the escape of shavings or cuttings of the wood portion of the said 25 pencil.

With the foregoing and other objects in view, the invention consists in the details of construction, and in the arrangement and combination 30 of parts to be hereinafter more fully set forth and claimed.

In describing the invention in detail, reference will be had to the accompanying drawing forming part of this application, wherein like characters denote corresponding parts in the several 35 views, and in which—

Figure 1 is a perspective view of a lead pencil sharpener embodying the invention;

Figure 2 is a perspective view thereof, with a 40 lid or cover removed;

Figure 3 is a sectional view of the pencil sharpener with the lid in place;

Figure 4 is a sectional view of the pencil sharpener on the line 4—4 of Figure 7 with the lid applied;

Figure 5 is a longitudinal sectional view on the line 5—5 of Figure 7;

Figure 6 is a longitudinal sectional view on the line 6—6 of Figure 7;

Figure 7 is a view in elevation of the rear of 45

one form of the pencil sharpener, with the lid omitted;

Figure 8 is an underneath plan view of the lid as modified;

Figure 9 is a longitudinal sectional view on the 5 line 9—9 of Figure 8; and

Figure 10 is a view in elevation of a modified 10 spring for holding the blade in operative position.

In carrying the invention into practice, according to the present embodiment of the invention, a rectangular box-like body *a* is employed, through which a screw *b* extends whose threads engage threads of a cover or lid *c*. It is shown 15 in Figure 4 that the body is countersunk to afford a clearance for the head of the screw. A blade *d* is interposed between the convex surface *e* of the body and the cover *c*, it being shown that the cover has marginal flanges or ribs *c'* which 20 align with grooves or recesses *f* and *f'* over which grooves the longitudinal edges of the blade *d* project and when the screw is turned to draw the cover inwardly, a pressure is exerted on the blade near its edges so that it is stiffened to 25 withstand the cutting action when operating on the pencil.

Preferably, at one end, the body is provided with a guiding channel *g* which tapers from the outer end to the inner end thereof and it is disposed at such angle to the knife that when a pencil is introduced or pushed into the guiding 30 channel and turned, the side of the pencil will be shaved or cut to a taper or point. The taper of the channel *g* and its relation to the groove *f* 35 over which the knife lies is shown in dotted lines in Figure 2.

The body is also shaped or cut to form a longitudinal slot *h* which merges with the groove *f* and the cover *c* has its edge recessed as at *i* to 40 form a clearance for shavings or cuttings which escape through the groove *f* and beveled outer surface as at *c'* to aid in the escape of the cuttings.

The lid is shown as seated in a recess between 45 flanges or shoulders *k* and *k'* produced in the formation of the body. The said body has box-like recesses *p* formed as a part of its structure and resilient or yielding pins or studs *n* and *n'*, 50 which are anchored in the body, project into the box-like recesses which are separated by a partition *r*.

At the inner end of the channel or pencil guide 55 *g* a collecting box *l* is formed in the body and the

material of the body is shaped to produce a clearance or recess *i* at the upper edge of the cover.

The blade *d*, which may be of ordinary type, is provided with the usual apertures *d*² which receive the pins *n* and *n'* of this invention, and the central hole *s* of the blade receives the screw *b*. If the size of the blade is not normal it may yet be used in this device by reason of the fact that the pins or studs *n* and *n'* are yieldable or resilient and they may be held in engagement with the apertured portions of the blade so that the blade may be held under pressure or tension with its cutting edge in operative relation to the channel in which the pencil is placed and manipulated. The relation of parts is such that the studs *n* and *n'* engage the blade at the edges of the apertures and exert pressure as stated to hold the blade with its cutting edge in operative relation to the channel in which the pencil is rotated. Other means or a modified construction may be employed for accomplishing the result of holding the blade in operative relation to the pencil and one such modification is shown in Figures 6 and 7, wherein a spring *o*, here shown as a flat member seated edgewise in the partition *r* has its ends embracing the pins *n''* and *n'''* and the spring is so shaped that it will exert force on the pins *n''* and *n'''* in the direction of the channel in which the pencil is manipulated. In order to accomplish this result, the aperture *s* in the blade is slightly larger than the screw *b*.

As a further modification for accomplishing the result of holding the blade in operative relation to the pencil, a modified cover such as *C* will be provided with posts or studs *n⁴* and *n⁵* which will fit into holes of the blade and preferably the studs are provided with jackets *q* of resilient material which will have the effect of exerting pressure on the blade to force its cutting edge into operative relation to the pencil.

In the forms of the invention shown in Figures 2 to 7, the cover *c* will not be provided with studs, but the posts *n'*, *n* or the pins *n'', n'''* will be relied upon to effect the result.

Figure 10 shows a further modified means for holding the blade in operative position to the pencil and this comprises a spring *o'* similar to the spring *o* which may be anchored in the body in the same manner as the spring *o* and as a substitute therefor, but in this modified form, the spring is shaped with upwardly projecting lugs *o³* at its ends which are intended to enter the apertures of the blade and perform the same function as the members *n''* and *n'''* of that form of the invention shown in Figure 6.

In order to render this pencil sharpener available for pencils smaller than the normal pencils, a guide plate *m* may be provided which is oscillatable on a pin or stud *a'* anchored at the end of the body, and the said guide plate will have an aperture *g'* smaller than the channel *g*. The said plate may be swung clear of the end of that portion of the body having the channel *g* when pencils of normal size are to be sharpened, or it may be swung to cover a portion of the end of the body with its aperture *g'* in registry with the channel *g*.

We claim:

1. A pencil sharpener using safety razor blades consisting of a rectangular blade carrier having a guiding channel for the reception of a pencil and a receptacle at its inner end, a blade support formed as a part of the body and the said body having grooves at the edges of the blade

support, said support being of a width to hold a blade with its edges overlying the grooves, the said body having recesses on each side of the blade support, blade engaging studs anchored in the body and projecting into the recesses and occupying holes of the blade, resilient means for forcing the studs toward the guiding channel whereby the blade is forced into operative relation with a pencil in the guiding channel, a cover for the blade having ribs engaging the upper surface of the blade at its edges, and a screw rotatable in the body passing through a hole in the blade, the said screw being in threaded engagement with the cover and operative to exert a pull on the cover to force the ribs of the cover into engagement with the blade, whereby the said blade is flexed, the said cover and blade having clearances for the escape of cuttings during the pencil sharpening operation.

2. A lead pencil sharpener using safety razor blades consisting of a rectangular blade carrier having a guiding channel for the reception of a lead pencil and a receptacle at its inner end, a blade support formed as a part of the body and the said body having grooves at the edges of the blade support, said support being of a width to hold a blade with its edges overlying the grooves, the said body having recesses on each side of the blade support, flexible blade engaging studs anchored in the body and projecting into the recesses and occupying holes of the blade, resilient means for forcing the studs toward the guiding channel whereby the blade is forced into operative relation with a pencil in the guiding channel, a cover for the blade having ribs engaging the upper surface of the blade at its edges, and a screw rotatable in the body passing through a hole in the blade, the said screw being in threaded engagement with the cover and operative to exert a pull on the cover to force the ribs of the cover into engagement with the blade, whereby the said blade is flexed, the said cover and blade having clearances for the escape of cuttings during the pencil sharpening operation.

3. A pencil sharpener using safety razor blades consisting of a rectangular blade carrier having a guiding channel for the reception of a pencil and a receptacle at its inner end, a blade support formed as a part of the body and the said body having grooves at the edges of the blade support, said support being of a width to hold a blade with its edges overlying the grooves, the blade support having its upper surface transversely convex, the said body having recesses on each side of the blade support, blade engaging studs anchored in the body and projecting into the recesses and occupying holes of the blade, resilient means for forcing the studs toward the guiding channel whereby the blade is forced into operative relation with a pencil in the guiding channel, a cover for the blade having ribs engaging the upper surface of the blade at its edges, and a screw rotatable in the body passing through a hole in the blade, the said screw being in threaded engagement with the cover and operative to exert a pull on the cover to force the ribs of the cover into engagement with the blade, whereby the said blade is flexed, the said cover and blade having clearances for the escape of cuttings during the pencil sharpening operation.

4. A lead pencil sharpener using safety razor blades consisting of a rectangular blade carrier having a guiding channel for the reception of a lead pencil and a receptacle at its inner end, a blade support formed as a part of the body and

- the said body having grooves at the edges of the blade support, said support being of a width to hold a blade with its edges overlying the grooves, the blade support having its upper surface transversely convex, the said body having recesses on each side of the blade support, flexible blade engaging studs anchored in the body and projecting into the recesses and occupying holes of the blade, resilient means for forcing the studs 5 toward the guiding channel whereby the blade is forced into operative relation with a pencil in the guiding channel, a cover for the blade having ribs engaging the upper surface of the blade at its edges, and a screw rotatable in the body passing through a hole in the blade, the said screw being 10 in threaded engagement with the cover and operative to exert a pull on the cover to force the ribs of the cover into engagement with the blade, whereby the said blade is flexed, the said cover and blade having clearances for the escape of 15 cuttings during the pencil sharpening operation, and a plate pivoted directly to the end of said body adjacent a channel to cover and uncover the channel, said pivoted plate having a pencil receiving opening therein of less diameter than the channel and concentric thereto upon the plate being in position to cover the channel.
5. A pencil sharpener using safety razor blades consisting of a rectangular blade carrier having a guiding channel for the reception of a pencil and 20 a receptacle at its inner end, a blade support formed as a part of the body and the said body having grooves at the edges of the blade support, said support being of a width to hold a blade with its edges overlying the grooves, the blade support 25 having its upper surface transversely convex, the said body having recesses on each side of the blade support, a cover for the blade having ribs engaging the upper surfaces of the blade at its edges, a screw rotatable in the body passing 30 through a hole in the blade, the said screw being in threaded engagement with the cover and operative to exert a pull on the cover to force the ribs of the cover into engagement with the blade, whereby the said blade is flexed, the said cover 35 and blade having clearances for the escape of cuttings during the pencil sharpening operation, said carrier and cover forming cooperating parts, and blade engaging studs anchored in one of said parts and projecting into recesses, said studs 40 being arranged to engage holes of the blade to retain the blade in operative relation to a pencil in the channel.
6. A pencil sharpener using safety razor blades consisting of a rectangular blade carrier having 45 a guiding channel for the reception of a pencil and a receptacle at its inner end, a blade support formed as a part of the body and the said body having grooves at the edges of the blade support, said support being of a width to hold a blade 50 with its edges overlying the grooves, the blade support having its upper surface transversely convex, the said body having recesses on each side of the blade support, a screw rotatable in the body passing through a hole in the blade, the 55 said screw being in threaded engagement with the cover and operative to exert a pull on the cover to force the ribs of the cover into engagement with the blade, whereby the blade is flexed, the said cover and blade having clearances for 60 the escape of cuttings during the pencil sharpening operation, and blade engaging studs anchored in the cover and projecting therefrom to occupy holes of the blade and retain the blade in operative relation to a pencil in the channel.

5. A lead pencil sharpener using safety razor blades consisting of a rectangular blade carrier having a guiding channel for the reception of a lead pencil and a receptacle at its inner end, a blade support formed as a part of the body and the said body having grooves at the edges of the blade support, said support being of a width to hold a blade with its edges overlying the grooves, the blade support having its upper surface transversely convex, the said body having recesses on each side of the blade support, flexible blade engaging studs anchored in the body and projecting into the recesses and occupying holes of the blade, resilient means for forcing the studs toward the guiding channel whereby the blade is
